CLAIM

The ornamental design for a medical device delivery system handle as shown and described.

DESCRIPTION

FIG. 1 is a perspective view of a medical device delivery system handle showing our new design.

FIG. 2 is another perspective view of the medical device delivery system handle.

FIG. 3 is a first side view of the medical device delivery system handle.

FIG. 4 is a second side view of the medical device delivery system handle.

FIG. 5 is a third side view of the medical device delivery system handle.

FIG. 6 is a fourth side view of the medical device delivery system handle.

FIG. 7 is a first end view of the medical device delivery system handle; and,

FIG. 8 is a second end view of the medical device delivery system handle.

The broken lines showing portions of the medical device delivery system handle are for illustrative purposes only and form no part of the claimed design.
